UNITED STATES PATENT OFFICE.

WILLIAM A. CHRYSST, OF DAYTON, OHIO, ASSIGNOR TO THE DAYTON ENGINEERING LABORATORIES COMPANY, A CORPORATION OF OHIO.

ENGINE-STARTING SYSTEM.

1,427,067.

Specification of Letters Patent. Patented Aug. 22, 1922.

Application filed September 19, 1917. Serial No. 192,202.

To all whom it may concern:

Be it known that I, WILLIAM A. CHRYSST, a citizen of the United States of America, residing at Dayton, county of Montgomery, 5 and State of Ohio, have invented certain new and useful Improvements in Engine-Starting Systems, of which the following is a full, clear, and exact description.

This invention relates to an improvement 10 in electric starting devices for internal-combustion engines, and more particularly to that type of starting devices, wherein a dynamo-electric-machine is operable as a motor for starting purposes and as a generator 15 for charging and other purposes.

One of the objects of the present invention is to provide a simplified starting system, wherein the operator is required to effect 20 only a single operation, the remaining sequence of operations being effected automatically.

Another object of the present invention is to provide a starting system which is small in size, compact and simple in construction, 25 and sure and efficient in operation.

Further objects and advantages of the present invention will be apparent from the accompanying drawings, wherein one preferred form of the present invention is 30 clearly illustrated.

In the drawings:

Fig. 1 is a top plan view of a portion of an automobile chassis and engine, showing the several units of the present system 35 mounted thereon and their relative positions thereto.

Fig. 2 is a view, partly in section and partly in elevation, of the connecting or reduction gearing embodied in the present invention.

Fig. 3 is a sectional view, taken on the line 3—3 of Fig. 2, illustrating the eccentric or "Hunting-tooth-gear" embodied in the reduction gearing.

Fig. 4 is a view, taken on the line 4—4 of Fig. 2, of an over-running clutch embodied in the reduction gearing.

Fig. 5 is a front-end view of the dynamo-electric-machine, a portion of the front-end 50 casing being broken away to show the commutator brush controlling solenoid and the controlling element of the brake ring embodied in the reduction gearing.

Fig. 6 is a diagrammatic view of the elec-

trical devices, circuits and connections embodied in one form of the present invention.

Fig. 7 is a detail sectional view, taken on the line 7—7 of Fig. 2.

Fig. 8 is a view, partly in elevation and partly in section, taken on the line 8—8 of Fig. 2.

Referring to the drawings, wherein one preferred embodiment of the present invention is illustrated, the numeral 20 designates the side frames of an automobile chassis, which support an engine 21 mounted on the cross bars 22.

The engine 21 may be of any standard type, but for the purposes of illustration an engine of the 4-cylinder, 4-cycle type has been illustrated. This engine has the usual crank shaft 21^a, one end of which is connected to the flywheel and clutch mechanism, designated by the numeral 21^b (see Fig. 1), while the opposite or front end of said crank shaft has a belt or chain connection 24 with the electric machine 23.

The dynamo-electric-machine, as will appear hereinafter, is operable as a motor for starting purposes and as a generator for charging and other purposes.

Referring to Figs. 1 and 6, the electrical circuits and connections embodied in the dynamo-electric-machine, and the other parts of the system, are clearly shown. This dynamo-electric-machine comprises the side frames 25 within which an armature 26 is adapted to operate; these side frames 25 support the series-field winding 27 and the shunt-field winding 28.

The storage battery 29 forms a source of current which is adapted to supply current to the electric machine for operation as a motor for starting purposes and is adapted to receive current from the electric machine when the same is being driven by the engine as a generator.

The circuit connections and arrangements between the electric machine and the storage battery, and the controlling devices forming a part of said connections, will now be described: Suppose that the engine 21 is at rest and that it is desired to bring the same into operation. The operator will exert pressure on the controlling element 30, which will tend to close the contacts 31 and 32 of the controlling switch, thereby causing a flow of current to pass through the follow-

ing circuit: From the battery 29, through conductor 33, conductor 34, through the contact plates 31 and 32, conductor 35, to the solenoid 36.

5 By referring to Fig. 6, it will be apparent that initially the flow of current through the series-field winding 27 will be prevented, for the reason that the series-field circuit is normally broken, due to the raised position 10 of the motor commutator brush 37.

As the current passes through the solenoid 36, it will return to the negative side of the battery, through the conductor 38, ground connections 39 and 40, and conductor 15 41. This flow of current, which of course may be regulated to give any desired strength of flow, will immediately energize 20 the solenoid 36, and this in turn will attract the lever 42, which is pivoted as at 43, and 25 tend to move said lever in the direction of the arrow "A" (see Fig. 6). This lever 42 normally engages at one end with the brush holder of the motor brush 37, and, under the influence of the spring 44, tends to 30 maintain said brush in raised position, relative to the motor commutator 45, of the armature 26, overcoming the tension of the spring 47.

As soon as the lever armature 42 is attracted by the solenoid 36, the spring 47 will tend to force the brush 37 into contact with its commutator 45, thus closing the motor circuit through the following circuit connections: from the conductor 35, 35 through the series-field winding 27, to the brush 37, via the conductor 48, thence across the armature windings, to the opposite motor commutator brush 49, back to the negative side of the battery, via the ground connections 50 and 40, and conductor 41.

As has been explained above, the energization of the solenoid 36 results in the shifting of the commutator brush into circuit closing position, and this same solenoid, 45 by its attraction of the lever armature 42, tends to bring into effect a reduction gear connection between the armature of the electric machine and the front end of the crank shaft 21. The manner in which this 50 reduction gear connection is effected, will be described hereinafter in connection with the description of the mechanical members of the present invention.

As soon as the electric machine, operating 55 as a motor, cranks the engine through the reduction gearing sufficiently to bring the engine into operation, the operator will release the controlling element 30, thus breaking the circuit through the series-field winding 27 and the solenoid 36, by opening the main circuit at the contacts 31 and 32.

By the construction of the connecting, or reduction, gearing, referred to more particularly hereinafter, the ratio will be changed 60 so that during the operation of the electric

machine as a motor, it will operate at a relatively high speed as compared to the speed of the engine, while, when the engine becomes self-actuating, it will tend to drive the electric machine through certain parts of this reduction, or connecting, gearing at substantially the same speed as the speed of the engine; of course this speed ratio can be changed within certain limits to meet required conditions. 75

When the engine drives the electric machine as a generator, current will initially flow from the positive generator brush 51, through the conductor 52, across the contact plates 53 and 54 of the controller switch, 80 through the conductor 55, to the point 56. Here the current will divide and a comparatively small portion will pass from the conductor 57, shuntfield winding 28, conductor 58, to the ground 39, thence to the opposite 85 commutator brush 59, via ground connection 50. The remaining part of the current will flow beyond the point 56, through the conductor 60, to the point 61, and initially through the fine wire winding 62 of 90 the circuit interrupter 63, thence to the ground connection 64, back to the opposite side of the generator, via the ground connection 50 and commutator brush 59.

As soon as the potential of the current 95 passing through the fine winding 62, energizes the circuit interrupter 63 sufficiently to attract the armature 65, the contacts 66 and 67 will be closed, thus permitting the current to flow from the point 61, through the heavy series-winding 68, across the contacts 66 and 67, thence through conductor 69, to the opposite side of the battery 29, across said battery and back to the opposite side of the generator via the conductor 41, 100 grounds 40 and 50, and the negative commutator brush 59.

This generator circuit will be maintained as long as the voltage across the generator brushes exceeds the voltage across the battery terminals. The function of the circuit interrupter 63 is well understood, and further detailed description of the same is deemed unnecessary in the present application. 110

From the above description it will be apparent that the operator is required to make but a single operation, that is to press the button or controlling element 30 during the starting operation, so as to close the contacts 31 and 32. All of the other succeeding operations are effected automatically, and, as will appear hereinafter, the motor and generator gear connections are selected and brought into operation automatically, 115 without any further requirement on the part of the operator.

As has been described heretofore, the electric machine, when operating as a motor, tends to operate at a high speed and to 120

crank the engine at a comparatively low speed. This reduction in speed ratio is secured in the present instance by means of a connecting, or reduction, gearing which 5 is mounted in the front-end casing 70 (see Fig. 1) of the dynamo-electric-machine 23.

This reduction gearing is of course connected to the shaft 71 of the armature 26, in the manner described hereinafter. The 10 armature shaft 71 extends beyond the end wall 72 of the dynamo-electric-machine, and the reduced end portion of said shaft is adapted to fit within the stub-shaft 73, which may be termed—for the sake of convenience—the "clutch shaft." One end of this clutch shaft 73 rotates in the ball bearing 74, while the opposite end thereof is supported by the bearing 75, carried by the front-end housing 70. The armature shaft 20 71 is pinned to the clutch shaft 73 by means of a spline or key 76.

The end wall 72 of the electric machine is flanged at 77 to form a support for internal clutch member 82 which is secured to said 25 end wall 72 by means of screws 87. A clutch disc 78 provided with a lever 79, the function of which will be described herein-after, is supported for rotative movement upon member 82. Disc 78 carries studs 80^a 30 upon which are loosely mounted frictional elements or rollers 80. Rollers 80 are located in the space provided by notches 81 formed in the clutch member 82. Clutch member 82 is located within an external 35 clutch member or cup 83, loosely journalled upon the shaft 73. By moving disc 78, rollers 80 may be shifted therewith to lock the cup 83 with internal clutch member 82, which is stationary, and thus hold the cup 40 83 in fixed position.

The cup 83 is provided with a series of 45 openings 85 into which project rollers 84^a mounted upon studs 84 which are carried by an internal hunting tooth gear 86. The base of the cup serves as a retaining plate 50 for the gear 86 in a manner to be described later. This gear 86, which may be termed an "eccentric gear element," or "wobble gear" is mounted upon a series of roller bearings 55 88, which are mounted between the gear element 86 and an eccentric portion 89 of the clutch shaft 73.

The gear element 86 is also provided with 60 teeth 90, which, as will be described herein-after, are adapted to mesh with the teeth 91, formed on the internal face of the driven gear element 92. This gear element 92 includes a casing, and, on the interior of said casing, a cylindrical face is provided as at 65 93, which forms the outer wall of a frictional clutch between said casing and the clutch shaft 73.

A series of frictional rollers, designated 70 by the numeral 95, are positioned in tapered 65 grooves 95^a, formed in the enlarged por-

tion 96 of the clutch shaft 73. (For detailed construction of this frictional clutch, see Fig. 4.)

The driven gear element 92 terminates in a cylindrical portion 97, which surrounds 70 the one end portion of the clutch shaft 73. This cylindrical portion 97 is adapted to receive a pulley wheel or sprocket 98, over which the belt or chain 24 runs to connect the electric machine with the front end of 75 the crank shaft of the engine.

As a means for securely maintaining the front-end reduction, or connecting, gear, in its proper position relative to the armature 80 of the electric machine and the end wall thereof, a bolt 99, threaded at one end, passes through the outer end of the clutch shaft 73, and is secured home in a threaded aperture, formed in the end of the armature shaft 71. Then the opening, formed at the 85 end of the cylindrical portion 97, of the gear 92, is threaded to receive the nut 100.

The operation of the above described gearing will be as follows: When the operator has depressed the controlling button 30, to 90 cause current to flow from the storage battery 29, through the solenoid 36, the solenoid will attract the lever armature 42, which will tend to permit the main motor circuit to be closed by the depression of the normally 95 lifted commutator brush 37.

The movement of the armature lever 42, also tends to shift a lever 79, which is connected with the disc 78, and the shifting of this disc will tend to also shift the frictional rollers 80, which are mounted upon the disc, into locking engagement between the clutch element 82 and the retaining plate, or cup, 83. In reality this means that the cup 83 is locked to the end wall 72 of the 105 electric machine, inasmuch as the clutch element 82 is secured thereto, as has been explained heretofore.

Now, as soon as the current passing 110 through the motor windings of the electric machine tend to rotate the armature 26 of the electric machine, the armature shaft 71, and consequently the clutch shaft 73, will likewise be rotated.

The eccentric portion of the clutch shaft 115 73, operating against the roller bearings 88, which are positioned between the eccentric or wobble gear element 86 and the eccentric portion of said shaft, will rotate this eccentric gear in an orbital path about the axis of gear 92, but the gear will be held against axial rotation by the action of the rollers 84^a, which are carried by the gear, coming in contact with the walls of the openings 85 in cup 83.

The openings 85 are of greater diameter 120 than that of the rollers 84^a, as is clearly shown in Fig. 8, and this permits an oscillatory movement of the eccentric gear element 86, so that this gearing is oscillated 130

in such a manner that a portion of the teeth 90 thereof will mesh with a corresponding portion of the teeth 91 of the gear element 92. Gear element 92 will be rotated at a reduced speed relatively to the shaft 71.

This reduced speed of rotation of the gear element 92 will be transmitted to the pulley or sprocket element, and consequently to the engine crank shaft, through the belt or chain connection 24. The frictional clutch construction shown in Fig. 4, and which has been specifically described heretofore, of course permits the relative rotation of the gear element 92 and the clutch shaft 73, during this starting operation.

When the engine becomes self-actuating, and the speed thereof becomes greater than the speed of the clutch shaft 73, which is of course reduced to practically nothing as soon as the engine becomes self-actuating, due to the breaking of the main motor circuit by the operator releasing the button 30, the frictional clutch shown in Fig. 4 will become effective to lock the casing 92, and therefore the driven pulley or sprocket 98, to the clutch shaft 73, and this driving effect will, of course, be transmitted directly to the armature shaft 71.

During the operation of the electric machine as a generator, the gear element 92 will of course engage with the eccentric gear 86, and will tend to rotate not only the gear 86 but also the retaining plate, or cup, 83. This rotation of the retaining plate, or cup, 83 is made possible by the return movement of the disc or ring 78 to normal position, under the influence of the spring 44 (see Fig. 6). This releasing of the retaining plate, or cup, 83 from locked position, occurs immediately the operator releases the button 30 from its motor circuit closing position; therefore the eccentric gear 86 and the retaining plate, or cup, 83 will simply rotate idly during this generator operation.

If the starting button 30 is not released as soon as the engine becomes self-operative, the retaining plate or cup 83 will unlock itself automatically from the stationary clutch member 82 since the cup 83 will then be rotated by engine power and in a direction such as to unlock members 83 and 82. In this manner the reduction gearing will become inoperative the instant the engine begins to drive the armature shaft 91 directly through elements 92 and 96. In other words, the means which connects the dynamo-electric-machine with the engine is constructed so as to be responsive to the assumption by the engine of the work of driving the dynamo and in such a manner that the reduction gearing provisions included in said means become inoperative the instant the engine drives the dynamo through other connecting provisions which include elements 92 and 96.

While the form of mechanism herein shown and described constitutes a preferred form of embodiment of the invention, it is to be understood that other forms might be adopted, all coming within the scope of 70 the claims which follow.

What I claim is as follows:

1. In an engine starting device, the combination with an engine, of a starting device therefor including a dynamo-electric-machine operable as a motor for starting purposes and having a pair of commutator brushes, one of which is normally in raised position; a reduction gearing interposed between the dynamo-electric-machine and the engine; and electro-magnetic means under control of the operator for initially connecting up the reduction gearing, so that the electric machine operating as a motor will drive the engine at a reduced speed, and for actuating said normally raised commutator brush to close the circuit connection, whereby the electric machine will operate as a motor for starting purposes. 75 80 85

2. In an engine starting device, the combination with an engine, of a starting device therefor including a dynamo-electric-machine, operable as a motor for starting purposes, and having a pair of commutator brushes, one of which is raised to normally break the motor circuit; a reduction gearing interposed between the dynamo-electric-machine and the engine, including a roller clutch, normally inoperative; and electro-magnetic means under control of the operator for initially operating said roller clutch, to connect the reduction gearing so that the electric machine operating as a motor will drive the engine at reduced speed, and for actuating the raised commutator brush to close the motor circuit for starting purposes. 90 95 100 105

3. In an engine starting device, the combination with an engine, of a starting device therefor including a dynamo-electric-machine, operable as a motor for starting purposes, and having a pair of commutator brushes, one of which is raised to normally break the motor circuit; reduction gearing interposed between said machine and engine including a roller clutch, having its rollers normally inoperative; and means for shifting said rollers to operative position and for actuating the raised commutator brush to close the motor circuit for starting purposes. 110 115 120

4. In an engine starting device, the combination with an engine; of a starting device therefor including a dynamo-electric-machine operable as a motor for starting purposes; a shaft connected with said machine and provided with an eccentric and with an internal roller clutch element; a wobble gear mounted on said eccentric; rollers supported by said wobble gear; a 125 130

member journaled on said shaft and having holes into which said rollers extend for permitting wobbling movement of said wobble gear, said member providing an external roller clutch member; an internal roller clutch member supported by said machine; normally inoperative clutch rollers; manually controlled means for moving said rollers into wedging action between said clutch members; and an internal gear element mounted on said shaft, adapted to be driven by the wobble gear, provided with an external clutch portion cooperating with said shaft clutch portion, and connected with said engine. 15

In testimony whereof I affix my signature.

WILLIAM A. CHRYST.
